UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

SHELL FOR ROCK DRILLS

Application filed January 4, 1929. Serial No. 330,395.

This invention relates to rock drills, but more particularly to shells which serve as mountings for rock drills of the drifter type.

The objects of the invention are to reduce the weight of the shell to a minimum, to reduce the cost of manufacturing thereof and to obtain a rugged shell which will be capable of withstanding the severe strains to which shells of this type are subjected.

Other objects will be in part obvious and in part pointed out hereinafter.

In the drawings illustrating the invention and in which similar reference characters refer to similar parts,

Figure 1 is a plan view of the shell,
Figure 2 is a side elevation,

Figure 3 is a transverse view taken through Figure 1 on the line 3—3 looking in the direction indicated by the arrows,

Figure 4 is an elevation partly in section of a modification, and

Figure 5 is a view similar to Figure 4 showing another modified form of the invention.

Referring to the drawings and at first more particularly to Figures 1, 2 and 3, A designates generally a shell comprising in this instance a pair of channels B arranged in parallelism and in such manner that the legs C and D thereof extend outwardly.

The legs C in this instance form one side of guideways E through which the guides of a rock drill are adapted to slide upon longitudinal movement of the rock drill. The guideways E are formed on the other side by plates F which extend longitudinally of the channels B and are held in spaced relation with respect thereto by means of spacers or strips G of less width than the plates F.

In this instance the inner edge of the spacers G are adapted to engage the edge of the guides of the rock drill, although it will be apparent from Figure 3 that clearance may be provided here and that the edges of the plates F and the channel bar members may engage the guides. Lateral movement of the drill with respect to the shell is thus prevented. As illustrated, the plates F and the spacers G may be of somewhat less length than the channels B, and in this instance they

are secured rigidly in position by means of bolts H which extend through the plates, the spacers and the legs C, and are provided with nuts J for clamping these elements securely together. If desired, washers K shaped to conform to the inner-surfaces of the legs C may be interposed between said legs and the nuts J to provide suitable seating surfaces for the nuts.

The channels B are in this instance held in such spaced relation with respect to each other by means of brackets L and O that the body of the rock drill or any projections thereon may lie between the channels when the guides are positioned in the guideways E. The bracket L is disposed between the rearward ends of the channels B to which it may be bolted or otherwise suitably secured and has a bore P to receive rotatably the end of a feed screw Q whereby the rock drill may be actuated longitudinally of the shell. The bracket O is disposed between the forward ends of the channels B and has a bore R to act as a bearing for the forward end of the feed screw Q.

Means is provided for cooperation with suitable clamping means (not shown) whereby the shell A may be secured to a quarry bar or other support. To this end the shell is provided with a cone S which has integral lateral flanges T whereon the legs D are adapted to seat and to which said legs may be secured by means of rivets U in order to insure against lateral movement of the channels B at points intermediate their ends. The cone S is also provided with longitudinal flanges U which bear against the inner surfaces U of the channels B and are secured to the channels by means of rivets W.

Referring now to the modification illustrated in Figure 4 the shell designated generally by X comprises in this instance a pair of Z-bars Y having the usual legs Z and b. The legs Z extend in an outwardly direction and have plates c bolted or otherwise suitably secured thereto to form guideways d for the guides e of a rock drill f. The plates c may be held in spaced relation with respect to the legs by spacers g through which the securing means, such as the bolts h also

extend. In the present instance wearing plates *j* are interposed between the legs *Z* and the spacers *g* to serve as renewable wearing surfaces for the guides *e* of the rock drill.

- 5 5 The cone *S'* which serves as a support for the shell *X* in this instance has a pair of longitudinally extending flanges *k* which seat against the outer surfaces of the *Z*-bars and are secured thereto by means of rivets *o*.
- 10 10 Between the flanges *k* is a flat surface *p* upon which the inwardly extending legs *b* of the *Z*-bars are seated and to which said legs may be riveted.

In the modification illustrated in Figure 15 5, a pair of angle members *r* are arranged in parallelism and are secured to the cone *s* by means of rivets *t*, the cone *s* having an extension *u* which extends between the angles *r* and around one edge thereof. In this 20 20 modification as in the modifications shown in Figures 1 to 3, the guideways *E* of the shell are formed by plates *F* which are held in spaced relation with respect to the lateral legs *v* of the angles *r* by means of spacers *G*, 25 25 said plates *F* and spacers *G* being secured to the legs *v* by means of bolts *H* and nuts *J*.

I claim:

1. A shell for rock drills, comprising a pair 30 30 of *Z*-bar members arranged in parallelism, wearing members secured to one leg of said *Z*-bar members and forming one side of guideways through which the guides of a rock drill are adapted to slide upon longitudinal movement of the drill, brackets interposed between the ends of said members and connected thereto to hold said members in spaced relation to accommodate the body of the rock drill, plates extending longitudinally of the members and adapted to form the other side 35 35 of said guideways, and means for holding the plates in spaced relation with respect to the members, said means being disposed between the plates and the wearing members on said leg of the *Z*-bar member and engaging the guides of the rock drill to prevent lateral movement of the rock drill with respect to the shell.

2. A shell for rock drills, comprising a pair 50 50 of *Z*-bar members arranged in parallelism, wearing members secured to one leg of said *Z*-bar members and forming one side of guideways through which the guides of a rock drill are adapted to slide upon longitudinal movement of the drill, brackets interposed between the ends of said members and connected thereto to hold said members in spaced relation to accommodate the body of the rock drill, plates extending longitudinally of the members and adapted to form the other side 55 55 of said guideways, means for holding the plates in spaced relation with respect to the members, said means being disposed between the plates and the wearing members on said leg of the *Z*-bar member and engaging the guides of the rock drill to prevent lateral 60 60 movement of the rock drill with respect to the shell, and means connected to the other leg of the *Z*-bar members and to the web between said legs to prevent flexion of said members.

70 70 In testimony whereof I have signed this specification.

CHARLES C. HANSEN.
